(57) CLAIM

The ornamental design for a beverage container having a counter and timer, as shown and described.

DESCRIPTION

FIG. 1 is an exploded front elevational view of a beverage container having a counter and timer showing my new design, the lid in open position;

FIG. 2 is a rear elevational view thereof;

FIG. 3 is a right side view thereof, the left side view being a mirror image of the right side view;

FIG. 4 is a top plan view thereof;

FIG. 5 is a bottom plan view thereof;

FIG. 6 is a perspective view thereof;

FIG. 7 is an exploded perspective view showing the lid portion only of a beverage container having a counter and timer with the body removed for ease of illustration showing a second embodiment of my new design;

FIG. 8 is an exploded left side view of the entire second embodiment of the beverage container having a counter and timer; and,

FIG. 9 is a perspective view of a beverage container having a counter and timer showing a second embodiment of my new design.

The broken lines in the drawings are included for the purpose of illustration and form no part of the claimed design.
